METHOD AND DEVICE FOR HUMIDIFYING
MIXTURES FOR NARCOSIS

Ernst Silten, Berlin, Germany

Application December 10, 1935, Serial No. 53,707

10 Claims. (Cl. 128—192)

This invention relates to inhalation apparatus, more particularly to an apparatus adapted for producing narcosis in a patient, such as by the use of ether or the like.

5 In an apparatus of this character, it is desirable to heat the mixture of the anaesthetic or medicinal and air to a sufficient extent so that the temperature of the mixture will be comparable to the body temperature. This is desirable because of 10 the disturbances likely to occur in the patient by reason of a low temperature of the inhaled mixture. However, in the heating of the mixture to the proper temperature, the relative humidity thereof is considerably decreased, as can be readily 15 appreciated, by the increase in temperature. It has been found that such a mixture, even though at the proper temperature, may result in symptoms of irritation of the patient.

The present invention is directed to the elimination of such disadvantage and it resides primarily in the idea that such irritation may be avoided by adding to the warmed mixture to be inhaled, a sufficient amount of moisture in order to raise the relative humidity to a desired amount. 20 This may be accomplished by causing the warm mixture to pass over a water surface, whereby it becomes partially saturated with the water, after which it may be inhaled. However, in vaporizing the moisture, some drop in temperature may take 25 place, in which case it is desirable to pass the moisture-laden mixture through a warm zone in order to again obtain the desired temperature. As an alternative, the mixture may be first heated to a temperature somewhat higher than the 30 final temperature so that in vaporizing moisture, the temperature of the mixture will be reduced to the proper point. There is a considerable advantage in first heating the mixture, as at the higher temperature the vaporization of water will 35 be faster and only a short time or a small surface of water will suffice to give the desired humidity.

In the accompanying drawing, constituting a part hereof, and in which like reference characters indicate like parts, the single figure is a side 40 elevational view of a form of apparatus made in accordance with the present invention, some parts being shown in section and some parts being broken away for clearness.

There is provided a receptacle 1 which may be 45 of glass for a vaporizable organic liquid such as ether, having an opening closed by cap 2. A regulating valve 3 operated by knob 4 has a tube 5 secured thereto, the end of said tube being visible through a sight opening in sleeve 6. Said 50 sleeve communicates with an opening in casing 7

having a shell 8 in the upper part thereof so positioned as to communicate with tube 5. An air valve 9 opening inwardly allows air to be drawn into the system. An outlet 10 from shell 8 is connected to one end of a coil 11 which is positioned within and substantially in contact with an electrical resistor heating element 12. The other end 13 of coil 11 communicates with hollow member 14, to the lower end of which is threaded a bottle or other container 15 having water 16 55 therein. The bottom of casing 7 is fitted with a cover plate 17 on which element 14 rests and which is held in place by cap 18. A tube 19 extends from a point below the liquid level in container 15 and out through the top of the 10 casing. A number of openings 20 are provided in the lower end thereof for the purpose stated below.

The upper end of tube 19 communicates with the T 21 into which is fitted a thermometer 22. 20 At the side thereof is secured a flexible tube 23 to the free end of which is fastened a mask 24 adapted to be placed over the face and having an exit tube 25. Inlet and outlet valves for air mixtures (not shown) are fitted to the mask. 25

A connection 26 from one end of resistor 12 is secured to one terminal of a temperature regulator 27 fitted into and held in plate 17. A connection 28 from the other terminal of said regulator is secured to a terminal of socket 29 containing lamp 30. The other terminal of said socket is connected by wire 31 to a source of electricity, which in turn is connected to the opposite end of resistor 12. The lamp 30 is placed in such a position as to illuminate the sight opening in 35 sleeve 6.

In order to support the device, I may provide a boss 32 on cap 18 to which a T member 33 having a bar 34 in the side thereof may be held in adjustable position by means of a screw 35 held 40 by a wing nut 36. The bar 34 may be secured to any desired support.

The operation of the device is as follows: The valve 3 is adjusted to cause a dripping of the ether from the end of tube 5 at the desired rate. 45 The regulator 27 is set at the proper temperature and the resistor is connected to a source of electricity. The mask 24 is placed over the face of the patient and as breathing starts, air is drawn in through valve 9, mixing with the vapors of 50 ether which have formed due to the elevated temperature within casing 7, and the mixture passes through coil 11, being heated to a desired temperature. The mixture passes into container 15 55 and sweeps over the surface of the body of water

16, passing out through openings 20 in tube 19. The mixture then passes upwardly through said tube and through a zone of elevated temperature and into T 21, through tube 23 and into the 5 mask 24. During the heating of element 12, the lamp 30 is lit illuminating the sight opening and making easier the observation of the rate of feed of the ether. The operation of the regulator 27 to disconnect the resistor will extinguish the lamp 10 30, thus indicating to the operator that the heat is not on. By reason of experience, he will be able to gauge whether the connection is broken temporarily because of the temperature within the casing, or whether due to a failure of the 15 apparatus and, if the latter, he will be enabled to take steps to correct the situation.

Although I have described my invention setting forth a single embodiment thereof, it will be apparent to those skilled in the art that various changes in the construction and operation of the device may be made within the scope of the invention. For instance, any type of heat regulator may be used and regulating means may be entirely dispensed with if desired. The positioning of the parts as well as their form, size and structure, may be varied at will. These and other changes may be made in my invention, the scope of which is defined by the claims appended hereto.

What I claim is:—

- 30 1. An apparatus for use for narcosis or inhalation purposes comprising a device for feeding a vaporizable organic liquid in predetermined amounts, means for mixing the same with air, an element for heating said mixture and means for introducing moisture into said mixture including a body of water and means for causing the preheated gaseous mixture to pass over the surface of the same.
2. An apparatus for use for narcosis or inhalation purposes comprising a device for feeding a vaporizable organic liquid in predetermined amounts, means for mixing the same with air, an element for heating said mixture and means for introducing moisture into said mixture including a body of water and means for causing the preheated gaseous mixture to pass over the surface of the same and means for heating said moist mixture.
3. An apparatus for use for narcosis or inhalation purposes comprising a device for feeding a vaporizable organic liquid in predetermined amounts, means for mixing the same with air, an element for heating said mixture and means for introducing moisture into said mixture including a body of water and means for causing the preheated gaseous mixture to pass over the surface of the same and a temperature regulator responsive to the temperature of said mixture for maintaining the temperature of said mixture constant.
4. An apparatus for use for narcosis or inhalation purposes comprising a receptacle for vapor-

izable organic liquid, means for feeding liquid into said receptacle, an air inlet in said receptacle, an outlet therefrom, a heating element, a conduit connected to said outlet and in proximity to said heating element, a container for water, the other end of said conduit being connected to said container, and an outlet from said container.

5. An apparatus for use for narcosis or inhalation purposes comprising a receptacle for vaporizable organic liquid, means for feeding liquid into 10 said receptacle, an air inlet in said receptacle, an outlet therefrom, a heating element, a conduit in the form of a coil having one end connected to said outlet and in proximity to said heating element, a container for water, the other end of 15 said conduit being connected to said container, and an outlet from said container.

6. An apparatus for use for narcosis or inhalation purposes comprising a receptacle for vaporizable organic liquid, means for feeding liquid 20 into said receptacle, an air inlet in said receptacle, an outlet therefrom, a heating element, a conduit connected to said outlet and in proximity to said heating element, a container for water, the other end of 25 said conduit being connected to said container, and a tube connected to said latter outlet and in proximity to said heating element.

7. An apparatus for use for narcosis or inhalation purposes comprising a casing, a receptacle 30 for vaporizable liquid in the upper part thereof, a heating element in said casing, a container for water in the lower part of said casing, a conduit between said receptacle to said container and adapted to be heated by said element and an outlet from said container.

8. A method of producing a vapor-air mixture for narcosis which comprises mixing a vaporizable organic liquid with air to give a gaseous mixture, thereafter passing said mixture in 40 proximity to a source of heat to warm the same, thereafter causing said mixture to come into contact with water, and conducting said mixture to an inhalation device.

9. A method of producing a vapor-air mixture 45 for narcosis which comprises mixing a vaporizable organic liquid with air to give a gaseous mixture, thereafter passing said mixture in proximity to a source of heat to warm the same, thereafter causing said mixture to pass over a body 50 of water, and conducting said mixture to an inhalation device.

10. A method of producing a vapor-air mixture for narcosis which comprises mixing a vaporizable organic liquid with air to give a gaseous 55 mixture, thereafter passing said mixture in proximity to a source of heat to warm the same, thereafter causing said mixture to come into contact with water, then warming said mixture, and conducting said mixture to an inhalation device. 60

ERNST SILTEN.
